Primary Examiner—Wallace R. Burke*Assistant Examiner*—M. H. Tung*Attorney, Agent, or Firm*—Lewis H. Eslinger; Jay H. Maioli**[57] CLAIM**

The ornamental design for a shutter for an optical disc cartridge, as shown and described.

DESCRIPTION

FIG. 1 is a top view showing my new design;
FIG. 2 is a left-side view thereof;
FIG. 3 is a front view thereof;
FIG. 4 is a right-side view thereof;
FIG. 5 is a back view thereof;
FIG. 6 is a bottom view thereof; and,
FIG. 7 is a perspective view.

FIG. 3

FIG. 5

FIG. 6

FIG. 4

FIG.7
